UNITED STATES PATENT OFFICE

FLOYD M. WILLIAMSON, OF DETROIT, MICHIGAN, ASSIGNOR TO CROSBY-ROSS WINDOW EQUIPMENT COMPANY, OF YPSILANTI, MICHIGAN, A CORPORATION OF MICHIGAN

SASH-CORD ARRANGEMENT FOR WINDOWS

Application filed July 13, 1928. Serial No. 292,579.

This invention relates to improvements in sash cord arrangements for windows, and refers more particularly to cord arrangements for windows wherein the sashes are 5 pivotally supported between the slides and are balanced by the cords and the weights on the latter during their pivotal movement between the slides as well as during the vertical movement of the slides and sash.

10 In my United States Patent No. 1,671,055 granted on May 22nd, 1928, the slides were provided with rollers around which the sash cords passed, and the ends of the latter were secured between the sides of the sash and the 15 plates attached to the slides. Such construction however has the following disadvantages: Firstly, in many cases the width of the slides necessitated the use of rollers of such small diameter that they would not operate satisfactorily; secondly, the cords were liable to break off near their ends as they were often cut through by the edge of the plates between which and the sides of the 20 sashes they were secured.

25 The present invention aims to provide a sash cord arrangement wherein cheap, light and easily attached sash cord guides are mounted on the slides, and have, even when employed with very narrow slides, sufficient 30 ly large radii to constitute satisfactory bearing surfaces for the cords, and wherein special mounting means are provided on the sides of the sash plates for holding the ends of the cords in such a manner that there is no liability 35 of the latter cutting and breaking off.

Having thus briefly and broadly stated the major purposes and advantages of the invention I will now proceed to describe it in detail with the aid of the accompanying drawings, in which:

Figure 1 illustrates a side elevation of a window with a sash pivotally mounted thereon and partly open.

Figure 2 is a section on the line 2—2 of 45 Figure 1 but showing the sash in nearly closed position.

Figure 3 is a disassembled view of the cord guide and part of the slide, and

50 Figures 4 and 5 are enlarged side and end views of the cord holder.

Referring to the drawings, 1 designates a hollow slide adapted to move vertically between window stops—not shown, and 2 indicates a longitudinal groove in the front wall of said slide. To the side of a sash 3 a plate 4 is secured; integral with the latter is a flange 5 which engages the groove 2 when the sash is in closed position. On the inner side of the slide wall 6 is a longitudinal raised portion 7.

60 A cord guide 8 is supported within the slide 1 as by screws 9. One side of this guide rests against the raised portion 7, and pads 10 and 11 at the ends of the guide bear against the inner side of the slide wall 6. A slot 12 extending longitudinally into the upper end of the guide forms a passage for a sash cord 14, and the inner side of this passage continues downwardly and is curved towards its lower end to form a rounded bearing surface 15 for the cord 14 as the latter is flexed to pass 65 through a longitudinally slotted opening 16 through the front of the slide. The pads 10 and 11 are intended to prevent air currents from passing through the hollow slide and 70 entering a room through the opening 16.

75 The outer end of the sash cord 14 is held in a collar 17 which is rolled after the cord is in place to insure the latter being firmly held; and integral with one end of the collar is an 80 eye 18 which is pivotally attached to the side of the plate 4 as by a screw 19 which passes through the latter and takes into the side of the sash 3. This arrangement permits the collar to turn as the direction of the cord 85 varies due to the amount of the sash opening. Moreover when the sash is closed the collar 17 passes into the opening 16. From the foregoing it will be seen that the possibility of the cord being cut by the end of the collar 90 is very remote.

95 20 designates a stop secured around the cord 14 to limit the pivotal movement of the sash; when the latter has been swung downwards to a predetermined limit the stop strikes the top of the guide 8 as shown at 20a. When steel sash cord is employed the cord guide is preferably made of a comparatively soft metal composition over which the cord 100 will easily slip.

As the sash 3 and plates 4 are swung pivotally about the slides 1 the weight of the former is counterbalanced by the weights (not shown) on the opposite ends of the sash cords 14, so that the latter are always held taut. Moreover as the sash 3 is raised or lowered the sash cords 14 move upwards and downwards under the cord guide 8 and around the rounded bearing surface 15 formed under the latter.

While in the foregoing the preferred embodiment of the invention has been described and shown, it is understood that the invention is susceptible to such modifications as fall within the scope of the appended claims.

What I claim as my invention and desire to secure by Letters Patent is:

1. A sash cord attachment for swinging windows having a hollow casing in which the window is pivoted; comprising a flat plate-like guide member mounted in the casing, elevated portions adjacent each end of the guide member abutting the wall of the casing, and a symmetrically curved portion on the guide about which the cord is trained to ride thereon when the window is swung to the open or closed position, the bearing surface of said guide being spaced from the elevated portions, and the space between one elevated portion and the guide forming a slot through which the sash cord passes.

2. A sash cord attachment for swinging windows having a hollow casing in which the window is pivoted; comprising a flat, elongated plate-like guide member formed with a cut-away portion between its ends to reduce its weight, elevated portions adjacent each end of the guide member abutting the wall of the casing, and a symmetrically curved portion on the guide extending lengthwise thereof from one end to a point adjacent the other end and about which the sash cord is trained to ride thereon when the window is swung to the open or closed position, the bearing surface of said guide being spaced from the elevated portions, and the space between one elevated portion and the guide forming a slot through which the sash cord passes.

FLOYD M. WILLIAMSON.
